COMPOUND FOR TREATING PETROLEUMS

James E. Cox, Oakland, Calif., assignor, by mesne assignments, to D. M. Dorman, Los Angeles, Calif.

No Drawing. Application October 29, 1934,
Serial No. 750,599

9 Claims. (Cl. 252—1)

The invention, in general, relates to means for conditioning petroleums for refinery operations, as well as to refining operations, per se. More particularly, the invention relates to a treating compound for quickly and efficiently breaking water-in-oil or oil-in-water emulsions, and also for recovering increased quantities of the gasoline fraction from petroleums, including refinery residuums, upon straight-run distillation.

One of the principal objects of my invention is to provide an efficient and inexpensively manufactured compound for dehydrating wet petroleums.

Another object of the invention is to provide a compound of the above mentioned character which is highly efficacious in dehydrating petroleums though used in but minute proportion to the quantity of the emulsion treated.

A further object of the invention is to provide a dehydrating agent for petroleums which is rapid and efficient in performance.

A still further object of my invention is to provide a dehydrating means for petroleums of the character above specified, which functions efficiently and quickly even though the treated oil be maintained at ordinary room temperatures, although a slight warming of the mixture, together with agitation, enhances dehydration as regards the time element.

Another object of my invention is to provide a compound for treating dry petroleums and/or refinery residuums which affords increased yields of gasoline fractions therefrom upon subjecting the petroleums or residuums to but ordinary straight-run distillation.

A still further object of the invention is to provide a treating compound for use in the refining of petroleums and adapted to be recurrently applied to residuums or bottoms of distilled petroleums thereby to enable the production of gasoline fractions from the treated residuums or bottoms by normal straight-run distillations.

Other objects of the invention, together with some of the advantageous features thereof, will appear from the following description and specification. While a preferred mode of preparing my treating compound, as well as the preferred compound itself, are hereinafter set forth, it is to be understood that I am not to be limited to the specific method of preparation described nor to the specified compound or compositions, inasmuch as the invention, as defined in the appended claims, can be embodied in a plurality and variety of forms and can be manufactured in a plurality and variety of ways. In other

words, the specification sets forth merely preferred modes of preparation of the compound and preferred compositions per se.

In its preferred form, the treating compound of my invention preferably comprises an admixture of a soap soluble in both oil and water, a solvent for said soap, together with a filtrate of a mixture comprising a shale sludge and an extract of tobacco, and a light petroleum distillate containing absorbed gases or ingredients obtained from said shale sludge.

One of the principal components of the treating compound of my invention consists of a sludge derived from shale, and I preferably utilize a shale of the character found in a drift located in Palomares Canyon, near Hayward, Alameda County, State of California.

The shale sludge for the compound may be prepared in a number and variety of ways, and either by employing a closed or a partially closed system, although I preferably used a closed system for manufacturing the sludge. It may be added here that a closed system is preferred because it has been found expedient to utilize the gases generated by the shale to assist in further activation of the shale.

In order to prepare the sludge forming a part of my compound, a quantity of the above-mentioned shale is suspended in water, and preferably with water that has seeped through a deposit of shale of the character referred to. The suspended shale is allowed to set, while continually feeding or passing the water through the same, until generation of gases has ceased. Preferably, the action is accelerated by intermixing calcium carbide with the water suspended shale, as well as by maintaining the temperature of the mixture around 98° F. While gases are being given off from the mixture, the sludge is being formed and is taken off, preferably by means of air under pressure, to a separate container.

The gases from the mixture of shale suspended in water and calcium carbide are passed through a light petroleum distillate, such as kerosene or a light lubricating oil stock, in order that ingredients desirable in the compound and which are given off by the mixture, and carried away in part by the gases (also in part by the shale sludge) may be absorbed by the distillate. This combination of a distillate and absorbed ingredients from the mixture hereinabove mentioned may be termed, for convenience, the "light concentrate" of the compound of my invention.

In accordance with the invention, the shale

sludge, as above described, is mixed with an aqueous extract of tobacco cuttings (approximately 3% by weight of cuttings used to the total amount, by weight, of shale used), and is 5 then filtered, the filtrate constituting what may be conveniently termed the "heavy concentrate" of my compound. If desired, the mixture of shale sludge and aqueous extract of tobacco may be distilled to remove excess water, the residue 10 plus the "tops" from distillation constituting the "heavy concentrate". Preferably, the proportion of shale sludge in the "heavy concentrate" to the quantity of extract of tobacco, as aforesaid, is approximately ten parts by volume of 15 the sludge to approximately one part by volume of the extract. The ratio of sludge to extract of tobacco may be varied to some extent without departing from the scope of the invention, as it is reasonable and I have found that different 20 emulsions as well as dry oils require different compositions of the same compound in order to obtain the most efficient and substantially uniform results. The "heavy concentrate" itself is a reasonably good dehydrator for wet petro- 25 leums.

In addition to the "light" and "heavy" concentrates hereinabove described, the compound of my invention includes means for forming thereof a difficult-to-disintegrate pseudo emulsion or 30 a moderately stable emulsion. The soap functions also to prevent the adherence of the compound, as well as mixtures of the compound and petroleums, to the walls of containers or pipes. Preferably, sodium oleate is used as the soap of 35 the compound, although any other suitable soap, such as sodium stearate or sodium palmitate may be employed, as desired. The latter two soaps, however, require excessive quantities of a solvent as well as the two "concentrates", in excess, to prepare an efficacious compound or solution. To dissolve the sodium oleate and hence 40 prepare it for intermixture with the two "concentrates", I preferably utilize either an acid, such as cresylic acid, or an oil, such as cresol or substances known commercially as "castor oil" and "castor machine oil". Approximately two to two 45 and one-half parts by volume of the solvent are used to one part by weight of the sodium oleate. The latter substance can be commercial sodium oleate but can be made, of course, by mixing a 50% sodium hydroxide solution with oleic acid.

For both treating a dry petroleum or a refinery 55 residuum to provide an increase in gasoline fraction derivable therefrom, as well as breaking a water-in-oil emulsion, I have found that admixtures of the foregoing named and described substances in the approximate proportions given in the following examples, will give excellent results, the formulae varying somewhat depending 60 upon the oil treated and in accordance with the water content thereof, the viscosity of the crude, and the impurities therein:

Example 1

	Per cent
Heavy concentrate	27
Light concentrate	27
Soap (preferably sodium oleate)	27
Solvent (preferably cresylic acid)	19

Example 2

Heavy concentrate	15
Light concentrate	30
Soap	15
Solvent	40

Example 3

	Per cent
Heavy concentrate	10
Light concentrate	20
Soap	25
Solvent	45

The more difficult-to-break emulsions are treated with the formula of Example 1, supra, while the less difficult-to-break emulsions are treated with the formulae of Examples 2 and 3. In other words, the formula containing the greater percentage of "concentrates" is employed for the more difficult-to-break emulsions, while a weaker solution, that is, containing lesser percentage of the "concentrates" is used for the more moderate or less difficult-to-break emulsions. I have found that approximately one part by volume of my compound to approximately two hundred and fifty parts by volume of the water-in-oil or oil-in-water emulsion will give efficient results at ordinary room temperatures. The efficiency of dehydration as regards time or rate of dehydration is aided if the mixture of compound and oil is moderately heated and the whole is subjected to agitation, which may consist of a steady, oscillatory movement.

As hereinabove stated, the compound of my invention is especially suitable for treating dry petroleums and/or refinery residua in order to obtain increased gasoline fractions therefrom upon straight-run distillations. The bottoms or residua of the treated and distilled petroleums or treated residua can be again or retreated with the compound and again subjected to straight-run distillation within the gasoline fraction range, and this cycle can be repeated and repeated. Either one of the formulae of Examples 1 to 3 inclusive, given above, may be applied to a petroleum or a refinery residuum for raising the gasoline fraction yield therefrom, although I have found that with extremely heavy, low A. P. I. gravity crudes and refinery residua the formula of Example 1, containing the greater quantity of concentrates is more suitable than the other formulae given. For relatively light crudes of higher A. P. I. gravity, the formulae of Examples 2 and 3 can be efficiently used. I have also found that the proportion of compound to oil treated varies somewhat in accordance with the character thereof, some oils requiring but one part by volume of the compound to approximately two hundred to two hundred and fifty parts by volume of the oil, while with respect to other oils, it requires one part by volume of the compound to approximately one hundred parts by volume of the crude. I have further found that once the proportion of compound to quantity of an oil treated is established, resulting in an increase in the yield of gasoline fraction derivable from such treated oil, an increase in the amount of compound added to the oil will not materially affect the yield of the gasoline fraction.

While I have been able to obtain increases in the yield of gasoline fraction upon straight-run distillation of a petroleum or a refinery residuum treated with the compound of my invention at ordinary room temperatures and with but slight agitation, I have found that still greater yields of gasoline fraction can be obtained from petroleums and refinery residua treated with my compound if the mixtures are subjected to great agitation and the temperature of the mixture during agitation is maintained approxi- 75

mately between 180° F and 220° F., the agitation and application of heat preferably being applied for approximately twenty to thirty minutes. Preferably, the last mentioned mode of treatment is carried out in a closed system.

5 Although it is possible to use the compound of my invention practically immediately after it has been prepared, I preferably allow the composition to set for a period of from twenty-four to forty-eight hours. This "conditioning" of the compound not only accelerates the rate of dehydration of a water-in-oil or an oil-in-water emulsion containing the "conditioned" compound, but also materially affects the amount, that is favorably, of the gasoline fraction obtainable from a treated crude. However, I have found it advantageous to allow a mixture of my "conditioned" compound and a dry petroleum or refinery residuum to set for an appreciable period of time before distilling the same. In other words, the important point in treating either water-in-oil emulsions for dehydration, or in treating a dry crude or residuum for increasing the gasoline fraction content thereof is the intimate contact of the compound of my invention with the treated oil.

It is to be understood that the appended claims are to be accorded a range of equivalents commensurate with the scope of the prior art.

I claim:

- 30 1. A composition for treating petroleums for dehydration of the same and for raising the gasoline fraction content thereof; said composition comprising a filtrate of a mixture of a shale sludge and extract of tobacco, a petroleum distillate containing absorbed ingredients of said sludge, and an emulsifying agent for said filtrate and said distillate; said agent comprising a soap, and a solvent for said soap.
- 40 2. A compound for treating petroleums and adapted to break water-in-oil emulsions as well as to increase the gasoline fraction content of a dry petroleum or a refinery residuum; said compound comprising a filtrate of a mixture of a shale sludge and extract of tobacco, and an emulsifying agent for said filtrate; said agent comprising a soap, and a solvent for said soap.

3. A composition for treating petroleums and adapted to dehydrate the same as well as to increase the gasoline fraction content thereof; said composition comprising a filtrate of a mixture of a shale sludge and an aqueous extract of tobacco, a petroleum distillate containing absorbed ingredients of said shale sludge, and an emulsifying agent for said filtrate and said distillate; said agent comprising sodium oleate, and cresylic acid.

4. A compound for treating petroleums and adapted to dehydrate the same as well as to increase the gasoline fraction content thereof; said compound comprising the residue and the tops of a distillate of a mixture of a shale sludge and an aqueous extract of tobacco, and an emulsifying agent for said residue and tops; said agent comprising a soap, and a light lubricating oil stock.

5. A dehydrator for water-in-oil emulsions, 20 said dehydrator comprising a filtrate of a mixture of a shale sludge and extract of tobacco.

6. A dehydrator for water-in-oil emulsions, said dehydrator comprising a filtrate of a mixture of a shale sludge and extract of tobacco, a 25 soap, and a solvent for said soap.

7. In a composition for treating petroleums, the residue and tops of a distillate of a mixture of a shale sludge and an aqueous extract of tobacco.

8. In a compound for treating petroleums and adapted to dehydrate the same as well as to increase the gasoline fraction content thereof, an emulsifying agent for a shale sludge and extract of tobacco; said agent comprising a soap, 35 characterized by sodium oleate, and a solvent for said soap, characterized by a light lubricating oil.

9. A composition for treating petroleums comprising a filtrate of a mixture of shale sludge and an aqueous extract of tobacco, a petroleum 40 distillate containing absorbed ingredients from said sludge, and an emulsifying agent for said filtrate and said distillate; said agent comprising sodium oleate, and castor machine oil.

45 JAMES E. COX.
